UNITED STATES PATENT OFFICE.

HAROLD G. BAXTER, OF BALDWIN, NEW YORK, ASSIGNOR TO WESTINGHOUSE ELECTRIC & MANUFACTURING COMPANY, A CORPORATION OF PENNSYLVANIA.

SWITCH MECHANISM.

Application filed May 17, 1920. Serial No. 381,914.

To all whom it may concern:

Be it known that I, HAROLD G. BAXTER, a subject of the King of Great Britain, and a resident of Baldwin, in the county of Nassau and State of New York, have invented a new and useful Improvement in Switch Mechanisms, of which the following is a specification.

My invention relates to switch mechanisms and particularly to quick-acting switch mechanisms for enclosed safety switches.

One object of my invention is to provide a mechanism for enclosed safety switches that shall effect quick actuation thereof.

Another object of my invention is to provide a mechanism, of the above-indicated character, that shall be simple and rugged in construction and reliable in its operation.

20 In the accompanying drawings, Figure 1 is a side elevational view of the switch box embodying my invention; Fig. 2 is an end view, partially in elevation and partially in section, of the box shown in Fig. 1; and 25 Fig. 3 is a plan view, partially in elevation and partially in section, of the operating handle of the box shown in Fig. 1.

A safety switching device 1 comprises a box 2 in which are disposed a switch 3, a 30 switch-actuating mechanism 4, safety fuses 5 and an operating handle 6 that extends into the box 2 and serves to operate the mechanism 4. The switch mechanism 4 comprises a rocker arm 7 for actuating the switch, a rocker cam member 8 that is secured to the arm 7, two rod members 9 and 10, mounted at the respective ends of the cam member 8, and two springs 11 and 12 that are slidably mounted on the rods 9 and 40 10, respectively. A cam member 13 is securely mounted on a sleeve member 14 that extends through the casing 2 and is adapted to receive a portion 15 of the operating handle 6 to which it may be secured by a 45 pin 16. The cam member 13 is adapted to alternately compress the springs 11 and 12, depending upon whether the switch is to be opened or closed. The cam member 8 is provided, at one end thereof, with two 50 notches 17 and 18, that are adapted to engage corresponding notches 17^a and 18^a, respectively, on a pivoted latching member 19. A spring 20 is secured to the latching member 19 and to co-operate with a stationary

member 21 for biasing and maintaining the 55 latching member 19 in such position as to restrain the action of the cam member 8. The latching member 19 has a portion thereof cut away whereby an arc portion 22 is formed that is concentric with the center 60 line passing through the portion 15 of the operating handle 6. A compressing member 23 that is turnably mounted on one end of the cam member 13 and is slidably 65 mounted on the rod 10, is adapted to so engage the arc portion 22 of the latching member 19, when the operating handle 6 has been moved to a predetermined position, as to disengage the latching member 19 from the cam member 8 to permit the cam member 70 to be actuated by the spring 11. A compressing member 24 is similarly mounted on the other end of the cam member 13 and on the rod 9.

When the switch 3 is to be opened, the operating handle 6 is so actuated as to compress the spring 11. The cam member 8 is prevented from actuating the switch 3 by the restraining action of the latching member 19. When the spring 11 has been compressed to a predetermined degree, the compressing member 23 engages the arc 22 of the latching member 19 and so actuates that member as to effect the release of the cam member 8. The compressed spring 11 is 85 then permitted to quickly open the switch 3.

When the switch 3 is to be closed, the cam member 8 is again restrained, by the co-operation of the notches 18 and 18^a, until the spring 12 has been compressed to a predetermined degree, whereupon the member 23 so engages the arc 22, of the latching member 19, as to disengage the latching member 19 and the cam member 8, to permit the actuation of the rocker arm 7 by 90 the cam member 8. By storing sufficient energy, to actuate the switch, in such manner that it may be released suddenly, a quick actuation of the switch is obtained.

The employment of the sleeve member 14 and the locking pin 16 permits the handle 6 to be removed during packing and shipping operations and permits a considerable saving in space.

Although I have shown a preferred form 105 of switch mechanism embodying my invention, I do not limit it to the structure illustrated, as various modifications may be

made therein without departing from the spirit and scope of the invention as set forth in the appended claims.

I claim as my invention:

6. 1. A quick-acting switch mechanism for a switch comprising an operating handle, a plurality of separate resilient members alternately energized thereby, a cam member for actuating the switch, and a latching member for precluding the actuation of the switch until the resilient members have been energized to a predetermined degree.
10. 2. Switch mechanism comprising a pair of levers pivoted intermediate their ends, separate spring members pivotally connecting the ends of the respective levers, a switch connected to one lever, a latch for controlling movement of the last said lever and operable to releasing position by the other lever.
15. 3. Switch mechanism comprising a pair

of levers pivoted intermediate their ends, rods for pivotally connecting the respective ends of the levers and permitting relative angular movement thereof, compression springs disposed on the rods for moving the levers, a latch means for controlling movement of one of the levers and operable by the other lever, and a switch connected to the lever controlled by the latch.

25. 4. A quick-acting switch mechanism comprising a switch-actuating means, a cam member for actuating the switch-actuating means, a plurality of resilient members disposed at the respective ends of the cam member, means for energizing the resilient members and means for restraining the cam member until the resilient members have been energized to a predetermined degree.

30. 35. In testimony whereof, I have hereunto subscribed my name this third day of May, 1920.

40. HAROLD G. BAXTER.
